UNITED STATES PATENT OFFICE.

HOWARD R. HUGHES, OF HOUSTON, TEXAS.

LUBRICATOR.

Application filed February 27, 1923. Serial No. 631,669.

To all whom it may concern:

Be it known that I, HOWARD R. HUGHES, a citizen of the United States, residing at Houston, Harris County, Texas, have invented a certain new and useful Improvement in Lubricators, of which the following is a full, clear, and exact description, such as will enable others skilled in the art to which it appertains to make and use the same.

10 My invention relates to an improvement in lubricators for use on roller boring drills in earth boring for oil, water, gas, sulphur, etc.

15 In the use of roller boring drills in deep wells it is common to use roller cutters on the forward end of the drill which are adapted to roll upon the formation being encountered and to thus disintegrate and cut away the material. These rolling cutters, working at some depth below the surface of the ground, must be supplied with lubricant in order to properly function. In such drilling it is common to attach the drill at the lower end of a hollow drill stem 20 through which flushing fluid is pumped downwardly through channels in the head of the drill in such manner as to project the fluid against the cutters and to force this fluid, carrying the cuttings in suspension, 25 upwardly outside of the drill stem to the surface of the ground. The drill, therefore works under a head of fluid standing in the well, and this fluid tends to work in around the bearings, under the high pressure at the 30 bottom of the hole, due to this head of fluid. This condition has to be taken into account in properly arranging a lubricator to supply a lubricant to the bearings against this fluid pressure.

26 In my prior Patent No. 930,759, issued August 10, 1909, I have shown a lubricator which is adapted to overcome these difficulties. The lubricator comprises a barrel attached to the head. This barrel is filled 35 with lubricant and a piston above the lubricant is forced downwardly against the same under the force of the flushing mud pumped through the drill stem by the pumps. There is the same head of fluid in the drill stem as 40 there is outside the drill stem, and besides this, there is an excess pressure due to the force of the pumps. This pressure is enough to force the lubricant out to the bearings against the pressure of the water in the hole. In this type of device, however, the 45 mud and sediment contained in the flushing

fluid will sometimes be forced past the piston into the lubricant itself, and thus interfere with the smooth working of the lubricant in the bearings.

It is the object of my present improvement to so arrange the lubricant and the piston that the flushing fluid will not be readily carried past the piston, and if leakage should occur, due to the faulty fit of the piston in the barrel, that the mud will not readily get to the bearings.

Referring to the drawing in which the preferred embodiment of my improvement is disclosed, I have shown therein a central 70 longitudinal section through the drill stem, the lubricator and the drill bit, part of the said drill bit being in elevation for greater clearness.

While my lubricator is adapted to be used 75 upon any type of roller boring drill, I have disclosed the same as being secured upon an ordinary type of Hughes cone bit having a head 1, provided with cone-shaped rolling cutters on the forward end thereof. The 80 upper shank of the bit is threaded at 3 for attachment to a drill collar 4 which serves to connect the bit to the drill stem 5.

Centrally of the upper end of the shank 3 is a threaded nipple 6 which serves as an attachment for my lubricating device. This nipple 6 is hollowed out centrally and connected by means of oil ducts 7 to the bearings of the rolling cutters.

My lubricator comprises a tubular barrel 8. This barrel is threaded at its lower end for connection with a coupling 9 of special construction, which serves to connect the lubricator to the nipple 6 of the bit. The coupling 9 is provided with a central channel 10 therethrough, which may be closed by means of a valve 11. The upper end of the lubricator barrel is closed by means of a cap 12 which is screwed firmly thereon. Toward the lower end of the barrel I provide an 100 opening 13 to allow the entrance of flushing fluid to the lubricator at that point.

Mounted centrally within the lubricator barrel is a smaller tube 14. This tube is supported at its upper end by being fitted 105 within a recess 15 at the lower face of the cap 12. The lower end of the tube 14 is threaded to fit within a recess 16 in the coupling 9. Adjacent the upper end of the tube is an opening 17 to admit the lubricant, 110 from the lubricant chamber to the tube.

Above the opening 13, within the lubrica-

22

tor, I provide a buoyant piston 18. This piston is annular in shape and is adapted to make a close fit with the inner surface of the lubricator barrel 8 and with the outer surface of the tube 14. It is made up from some light material, and preferably of some light metal, such as aluminum. It is shown as being hollow so as to include an air-tight chamber 19 therein to make the piston more buoyant. At the upper end of the buoyant chamber I have provided the usual packing rings or cups 20 which may be of leather, rubber or similar material, and secured to the body of the piston by means of set screws 21.

In the operation of a drill equipped with the type of lubricator shown, the flushing fluid, which is ordinarily a heavy mud, is pumped downwardly through the drill stem 20 5 to the bit and through the constricted channel 22 to the cutters. The flushing fluid, under the force of the pump pressure, will be directed through the opening 13 into the lubricant chamber below the piston. The buoyancy of the piston and the force of the flushing fluid will act to move the piston upwardly against the lubricant within the chamber 23. The lubricant will be thereby forced through the said tube, the channel 25 10 in the coupling, and the ducts 7 in the bit to the bearings of the cutters. If, due to a poor fit between the piston and the lubricator barrel, some of the mud is forced past the piston into the lubricant chamber 30 15 23, the heavy gravity of the mud will maintain it at the point below the lubricant, and will not tend to mix therewith, and to gravitate to the bearings as may be done in the ordinary type of lubricator. The liability of the mud or grit being allowed entrance to the bearings will thus be avoided. The operator will therefore be assured at all times that while the lubricator 35 20 25 is functioning the lubricant passing to the bearings, will be clear of grit or other substance tending to destroy the quality of the lubricant.

The further advantages of this arrangement will be apparent to one skilled in the

art without further description. What I claim as new, and desire to protect by Letters Patent is:

1. In a rotary earth-boring drill, a drill stem, a drill head thereon, roller cutters mounted on bearings on said head, a lubricator barrel secured to the upper end of said head within said drill stem, said barrel having an opening, for flushing fluid adjacent the lower end thereof, a buoyant piston in said barrel above said opening, a central 55 tube secured to said head within said barrel, said tube having an opening adjacent its upper end, and a passage from said tube through said head to said bearings.

2. In a rotary earth-boring drill, a drill stem, a head thereon, roller cutters mounted on bearings on said head, a lubricant barrel secured to said head within said drill stem, said barrel having an opening for flushing fluid adjacent the lower end thereof, a 60 buoyant piston in said barrel and means connected with the upper end of said barrel to conduct lubricant from said barrel to said head and through same to the said bearings.

3. In a rotary earth-boring drill, a drill 65 stem, a drill head thereon, roller cutters mounted on bearings on said head, a lubricator barrel within said drill stem, a piston in said barrel, buoyant means on said piston acted upon by the flushing fluid in said drill 70 stem to force said piston upwardly in said barrel and a tube leading from the upper end of said barrel to said head and ducts in said head connecting said tube and said bearings.

4. In a rotary earth-boring drill, a drill stem, a drill head thereon, roller cutters mounted on bearings on said head, a lubricator barrel in said drill stem having an opening adjacent its lower end, a buoyant piston above said opening, and a tube leading from the upper end of said barrel to said head, said head having ducts therein connecting said tube and said bearings.

In testimony whereof, I hereunto affix my signature, this the 24th day of February, A. D., 1923.

HOWARD R. HUGHES.
